FIG. 1

FIG. 2

INVENTOR

JOSEPH N. BORROUGHS

BY

Harry O. Schreder

ATTORNEY

UNITED STATES PATENT OFFICE.

JOSEPH N. BORROUGHS, OF OAKLAND, CALIFORNIA.

TOWEL CABINET.

Application filed April 16, 1923. Serial No. 632,250.

My invention is an improved towel cabinet.

The object of my invention is to provide a towel cabinet in which a new supply of towels may be placed, while a part of the previous 5 towel is still in the cabinet.

My invention comprises a mechanical method of dispensing towels as it is commonly designated, comprising feeding a web of toweling from a zig-zag pile in which the web 10 is folded backwards and forwards in a series of plies. The folded pile is placed on a shelf with a narrow slit at the side thereof, so that the web may be fed from the bottom of the pile. The web is drawn downwardly by a series of 15 feed rolls. My invention further contemplates attaching a clean folded pile of toweling to a nearly exhausted pile by means of attaching strings or tapes on the upper end of the lower pile and the lower end of the upper 20 pile, whereby a continuous supply of toweling may be dispensed for use.

The cabinet used has a narrow shelf which does not greatly exceed the size of the pile in width, and has a narrow slot through which 25 the web is drawn from the bottom of the pile. The hinged lid is used for the insertion of a clean towel pile. Feed rollers are located below the shelf and draw on the webbing, the weight of the pile and its narrow confines 30 causing sufficient resistance to maintain the web in proper alignment.

Another object is to provide a towel which is simple in construction and efficient in operation.

35 In the annexed drawing in which my invention is illustrated:

Figure 1 is a transverse sectional view of my cabinet.

Figure 2 is a fragmentary front view of 40 two towels secured together.

Referring more particularly to the drawing, my cabinet consists of a box 1 which has a door 2 hinged to the front thereof, and a cover 3 hinged to the top.

45 A towel supporting shelf 4 is mounted near the top of the cabinet and is hinged at 5 while the other side rests on blocks 6 formed on the walls of the box 1.

The towel is adapted to travel between a 50 roller 7 journaled in the walls of the box 1, and an idler roll 8, which presses against the roll 7 and is mounted on straps 9 which are

pivoted to the walls. A second pair of rollers 10 and 11 are positioned below the rollers 7 and 8,—the roll 10 is journaled in the walls 55 of the box 1, and the roll 11 is mounted on straps 12 which are pivoted to the box. The roll 7 rotates the roll 10 through suitable gearing 12a. The towel passes between rolls 7 and 8, through an opening 13 in the top of the door 2 and an opening 14 in the bottom of the door thence upwardly between the rolls 10 and 11 and then drops into the bottom of the box 1.

The folded towel 15 is placed on the shelf 4 and threaded through the box as described above. Strings 16 are formed on the end of the towel, to which the new towel is secured. The new towel now follows the preceding towel through the rolls and it is not necessary to 70 reread each new towel. This is very desirable since it requires no skill and is quickly done.

It will be noted that the shelf 4 and the compartment there-above for the folded towel 75 is not much larger in width, (that is, from front to back), than the zig-zag folded toweling in the pile. When the rolls for feeding the towel draw on the webbing they pull the lower folds; the weight of the pile, together with its narrow confines, in the towel compartment, gives a resistance to the withdrawal of the webbing, thereby preventing it from becoming twisted or otherwise disarranged in the feed roll.

Having described my invention I claim:

In a towel dispensing device, a cabinet having a towel compartment in its upper portion and a feeding roll compartment in its lower portion, a shelf separating said compartments and adapted to hold a supply of toweling, said cabinet having an upper opening to permit a portion of said toweling to pass therethrough to be exposed for use, and a lower opening to permit the used toweling to 90 pass back into the cabinet, a feeding roll disposed between said towel compartment and said upper opening to be actuated by the movement of the toweling thereover, and a second roll adapted to be actuated by said first 95 mentioned roll and operative to retract the used toweling back into the cabinet.

In testimony whereof I affix my signature.
JOSEPH N. BORROUGHS.
